[57] ABSTRACT

An improved analog-digital converter of the integrating type is provided for converting analog input voltages into accurately related digital outputs. The system operates during a first time interval (T_1) such that the analog input voltage charges a capacitor in a linear manner. The first time interval (T_1) is subdivided into a plurality of successive time periods (T_A). If, at the end of any time period (T_A), the voltage across the capacitor exceeds a predetermined threshold, a reference current is introduced into the capacitor to reduce the charge. The process is repeated for each time period (T_A), whenever the voltage across the capacitor exceeds the threshold at the end of such period. During a second time interval (T_2), the charging input voltage is removed from the capacitor, and the reference current is again introduced into the capacitor until the capacitor is discharged to a second predetermined level. The times the reference current is turned on are accumulated in an output counter which provides the digital output.

INTEGRATING TYPE ANALOG-DIGITAL CONVERTER

CROSS REFERENCE TO RELATED APPLICATION

This application is a continuation-in-part of copending application Ser. No. 249,077, filed May 1, 1972, and now abandoned for "Integrating Type Analog-Digital Converter."

BACKGROUND OF THE INVENTION

Integrating analog-digital converters, such as digital voltmeters, which produce a digital output signal that is representative of the time integral of an analog input signal, are known to the art. Such prior art converters require long conversion times to provide rejection of line frequency interference. Furthermore, such converters require large, expensive capacitors in the integrator circuit if high accuracy is desired. Also, such converters are limited in speed and accuracy by the gain, bandwidth and electrical noise of the comparator circuit.

The converter of this invention overcomes the major disadvantages of the prior art units. It allows a major increase in conversion rate while greatly reducing the value of the integrating capacitor and decreasing the gain-bandwidth requirements of the comparator circuit. The results are improvements in speed, accuracy, cost and complexity.

All the advantages of the prior art converters are retained such as accuracy independent of oscillator frequency and integration capacitor value drift, as well as high noise rejection.

BRIEF DESCRIPTION OF THE DRAWINGS

FIG. 1 is a block diagram schematically illustrating one embodiment of the invention;

FIG. 2 is a series of curves useful in explaining the operation of the system of FIG. 1; and

FIG. 3 is a block diagram schematically illustrating a second embodiment of the invention.

DETAILED DESCRIPTION OF THE INVENTION

In the system shown in FIG. 1, the input voltage E_{x_1} , representing the unknown analog quantity which is to be converted to a corresponding digital number is applied to input terminals 10. The input terminals 10 are connected to a voltage-to-current generator 12. The generator 12 may be any known type of circuit, and it serves to convert the input voltage into a current $I_1 = KEx_1$. In the particular embodiment, as shown by FIG. 1, the current I_1 is assumed to be positive.

The I_1 current is applied through an "and" gate 14 and through an "or" gate 16 to an integrator 18. The integrator 18 may be of any known type, and it includes a capacitor which is charged by the incoming current, and which develops a voltage E_c at the output of the integrator.

A reference current source 20 of any known type is also provided. The reference current source produces a reference current I_2 which, in the illustrated embodiment, is considered to be negative. The current I_2 is applied to a pair of and gates 22 and 24. Both of the and gates 22 and 24 are connected to the or gate 16, and to a further or gate 26. The or gate 26 is connected to a gate 28 and, so long as the current I_2 is flowing into the integrator 18, the gate 28 is enabled permitting an oscillator 30 to drive an output counter 32. The oscillator 30 may be a usual free-running multivibrator which

produces pulses at a recurring frequency (f_1). The output counter 32 is also designated N_o .

The system of FIG. 1 also includes further counters 34 and 36. The counter 34 is also designated N_1 , and it is used to establish an interval T_1 during which the current I_1 flows into the integrator 18. The counter 36 is also designated N_a , and it is used to establish a plurality of successive sub-time periods within the interval T_1 . Both the counters 34 and 36 may be driven by an oscillator 38. The oscillator 38 may also be a free-running multivibrator, and it may oscillate at a frequency f_o . The oscillator 38 may also be used to drive the output counter 32, through, for example, an appropriate frequency multiplier.

The system of FIG. 1 is put in operation, for example, by activating the oscillator 38 through an appropriate start circuit 40. The oscillator then drives the counters 34 and 36 until the counter 34 has reached the N_1 count, or some multiple thereof, corresponding to the time T_1 . At that time, the counter 36 has been driven through a predetermined number of time sub-periods N_a . At the end of the time N_1 , the counter 34 resets and the oscillator 38 is stopped. The counter 36, on the other hand, resets at the end of each time sub-period N_a .

The output of the counter 34 is applied to the set input terminal of a usual flip-flop 42, and also is used to reset the counter 34 after the N_1 count, and to stop the oscillator 38. The set output terminal of the flip-flop 42 is connected to the and gate 24. The output terminal of the counter 36, on the other hand, is connected to a pair of and gates 44 and 46. The and gate 44 is connected to the set input terminal of a flip-flop 48, and the and gate 46 is connected to the reset input terminal of the flip-flop. The flip-flop 48 is connected to the and gate 22. The output of the counter 36 is also used to reset the counter at the end of N_a count.

The voltage E_c developed at the output of the integrator 18 is connected to a threshold detector 50. The threshold detector 50 may be of any known type, and it produces an output at its terminal A whenever the voltage E_c at the output of the integrator is greater than a particular voltage E_1 , and the threshold detector develops an output at its terminal B whenever the voltage E_c is less than a selected voltage E_2 . The voltage E_2 is selected to be less than the voltage E_1 . The output terminal A of the threshold detector is connected to the and gate 44 and, through an inverter 52, to the and gate 46. The terminal B of the threshold detector is connected to the reset input terminal of the flip-flop 42. The output of the counter 34 is also connected through an inverter 54 to the and gate 14.

In the operation of the system, the start circuit 40 introduces a pulse (A in FIG. 2) to the oscillator 38 to start the oscillator. The oscillator then drives the counters 34 and 36. At the end of N_1 cycles, the counter 34 generates an output pulse (B in FIG. 2) designating the end of the time interval T_1 . During that time interval, the counter 36 produces a series of output pulses designating sub-time periods during the time interval T_1 (C in FIG. 2). The output pulse (B in FIG. 2) generated by the counter 34 is also used to reset the counter 34, as mentioned, and to stop the oscillator 38.

During the time T_1 , the and gate 14 is enabled since the counter 34 has not yet achieved its count (N_1), so that the flip-flop 42 is reset. Therefore, during the input interval T_1 , the current I_1 flows through the and gate 14

and through the or gate 16 (E in FIG. 2) into the integrator 18, producing a charge Q_x on the capacitor C in the integrator. The magnitude of the charge is:

$$Q_x = \frac{I_1 T_1}{C} \quad (1)$$

The time interval T_1 is subdivided into an integral number of sub periods of duration $T_1/4$, as represented by the curve C in FIG. 2. If at the end of any such sub period, the voltage E_c exceeds E_1 , as sensed by the threshold detector 50, then an output is produced at the output terminal A of the threshold detector which enables the and gate 44, so that the flip-flop 48 is set. This enables the and gate 22, and the reference current I_2 flows into the integrator. Since the current I_2 is of a polarity opposite to the current I_1 , the voltage E_c is reduced (curve F of FIG. 2), and an increment of charge Q_r is removed from the capacitor C in the integrator where:

$$Q_r = \frac{-I_2 T_1}{N_a C} \quad (2)$$

After the increment of charge is removed, the capacitor C in the integrator 18 continues to be charged by the current I_1 . If at the end of the next sub period N_4 the voltage E_c again exceeds E_1 , the foregoing process is repeated, as represented by the curve F of FIG. 2. The current I_2 is chosen so that at no time during the interval T_1 can the voltage E_c become negative.

Assuming that the voltage E_c was equal to E_2 at the start of the time interval T_1 , and that N_B units of charge equal to Q_r were removed from the capacitor C in the integrator 18 during the time interval T_1 , then, at the end of the time interval T_1 , the voltage E_c will be:

$$E_c = E_2 + \frac{I_1 T_1}{C} - \frac{N_B I_2 T_1}{N_a C} \quad (3)$$

During the time interval T_2 , which follows immediately after the time interval T_1 , the and gate 14 is disabled so that the current I_1 no longer flows into the integrator. During the interval T_2 , however, the and gate 24 is enabled so that the reference current I_2 flows into the integrator. The flow of the current I_2 into the integrator reduces the voltage E_c until a level of E_2 is reached, as sensed by the threshold detector 50. When the voltage E_c reaches the level E_2 , the flip-flop 42 is reset, cutting off the flow of the reference current I_2 into the integrator 18, and terminating the interval T_2 . The voltage E_c at the end of the terminal E_2 now equals E_2 , so that:

$$E_2 = E_2 + \frac{I_1 T_1}{C} - \frac{N_B I_2 T_1}{N_a C} - \frac{I_2 T_2}{C} \quad (4)$$

Therefore,

$$\frac{I_1 T_1}{C} - \frac{N_B I_2 T_1}{N_a C} - \frac{I_2 T_2}{C} = 0 \quad (5)$$

Therefore,

$$I_1 T_1 - \frac{N_B I_2 T_1}{N_a} - I_2 T_2 = 0 \quad (6)$$

The time interval T_1 is generated by accumulating N_1 cycles of the oscillator 38 of frequency F_o . Therefore:

$$T_1 = \frac{N_1}{F_o} \quad (7)$$

Similarly, each of the sub periods of T_1 are determined by a smaller number of cycles, so that:

$$\frac{T_1}{N_3} = \frac{N_1}{F_o N_1} \quad (8)$$

Each time the reference current source is turned on, the gate 28 is enabled, so that the output counter 32 counts at a rate of $F_1 > K F_o$. Therefore, during each sub interval during time T_1 , the output count N_{o1} accumulated is:

$$N_{o1} = \frac{T_1 F_1}{N_1} \quad (9)$$

If it be assumed that $F_1 = K F_o$, then:

$$\frac{T_1}{N_3} = \frac{N_{o1}}{K F_o} \quad (10)$$

Substituting (7) and (10) into equation (6), we have:

$$\frac{I_1 N_1}{F_o} - \frac{N_B I_2 N_{o1}}{K F_o} - I_2 T_2 = 0 \quad (11)$$

During the time interval T_2 , the output counter also accumulates counts at a rate of F_1 , due to the fact that the and gate 24 is enabled, therefore, during the interval T_2 the output count N_{o2} accumulated is:

$$T_2 = \frac{N_{o2}}{F_1} \quad (12)$$

Substituting equation (12) into equation (11), we have:

$$\frac{I_1 N_1}{F_o} - \frac{I_2 N_B N_{o1}}{K F_o} - \frac{I_2 N_{o2}}{K F_o} = 0 \quad (13)$$

Therefore,

$$I_1 N_1 - \frac{I_2 N_B N_{o1}}{K} - \frac{I_2 N_{o2}}{K} = 0 \quad (14)$$

Therefore,

$$I_1 N_1 = \frac{I_2}{K} (N_B N_{o1} + N_{o2}) \quad (15)$$

$$N_o = (N_B N_{o1} + N_{o2}) \quad (16)$$

Therefore,

$$N_o = \frac{I_1}{I_2} K N_1 \quad (17)$$

From equation (17), it will be observed that the output number N_o , which equals $N_B N_{o1} + N_{o2}$, is directly proportional to the input current I_1 , and therefore to the input voltage E_{x1} . It will also be observed from equation (15) that the output number N_o is independent of the value of the capacitor C in the integrator 18, and of oscillator frequency, provided that these parameters remain constant during a conversion. Therefore, high accuracy may be achieved easily and simply, since there is no dependence upon high tolerances insofar as the aforesaid parameters are concerned.

In the system and circuit of the present invention, since the maximum voltage across the capacitor C in the integrator 18 represents the full scale charge divided by $N_B/2$, substantial simplification in the threshold detector 50 may be realized, as compared with the usual prior art dual slope converter. Moreover, the system of the present invention is capable of faster conversions, for a given circuit, as compared with the prior art dual slope converter, since the maximum duration of the time interval T_2 is divided by a factor $N_B/2$.

Since the accuracy of the system of the invention is independent of the voltage E_2 , a feedback loop closed around the threshold detector 50 and the integrator 18 at the termination of a reading will insure that a measurement will start and finish precisely at the E_2 level, thereby eliminating the effects of temperature drift in the threshold detector.

Referring to the system shown in FIG. 3, wherein like parts in FIG. 1 are identified by the same reference character, the input voltage E_{x1} , representing the unknown analog quantity which is to be converted to a corresponding digital number, is applied to input terminals 60. The input terminals 60 are connected to a voltage-to-current converter 62. The converter 62 may be any known type of circuit, and it serves to convert the input voltage into a current $I_1 = KE_{x1}$. In the particular embodiment of FIG. 3, the current I_1 is assumed to be positive.

The I_1 current is applied through a current switch 64 to the summing node 66 of an integrator 68 which can be the same as integrator 18 of FIG. 1. It includes a capacitor which is charged by the incoming current, and which develops a voltage E_c at the output of the integrator.

A reference current source 20a produces a reference current I_2 which, in FIG. 3, is considered to be negative. The current I_2 is applied to a second current switch 72, the control input C of which is connected to gate 28a and, so long as the current I_2 is flowing into the integrator 68, the gate 28a is enabled permitting oscillator 30a to drive an output counter 74, which is also designated N_o . The system of FIG. 3 also includes counters 34a and 36a.

The system of FIG. 3 is put in operation, for example, by resetting counters 74, 34a and 36a with a short pulse from start circuit 40a, which simultaneously sets flip-flop 76, resets flip-flop 78 through or gate 80 and resets flip-flop 82 through or gate 84. The oscillator 38a then drives the counters 34a and 36a until the counter 34a has reached the N_1 count, or some multiple thereof, corresponding to the time T_1 . At that time, the counter

36a has been driven through a predetermined number of time sub-periods N_n . At the end of the time N_1 , the counter 34a produces a short pulse through differentiator 86 which resets flip-flop 76, thereby disabling and gate 88, stopping the counting process in counters 34a and 36a. The counter 36a, on the other hand, reaches a full count at the end of each time sub-period N_n and returns to a count of zero on the next pulse from oscillator 38a. Thus, each time a count of N_n is reached and counter 36a returns to its zero count state during time interval T_1 , a short pulse is issued through differentiator 90. If at this time, output A of threshold detector 50a is at a logical 1 ($E_c E_1$), and gate 92 is enabled and a pulse is applied to the set input of flip-flop 78.

15 The Q output of 78 enables and gate 44a which operates through or gate 96 to enable reference current switch 72 and also to enable and gate 28a, allowing oscillator pulses from oscillator 38a to be passed to counter 74. Alternatively, if, when the pulse from differentiator 90 is issued, the output A of threshold detector 50a is in the zero state, and gate 100 is enabled by inverter 102 and the reset input of flip-flop 78 is pulsed through and gate 100 and or gate 80. Current switch 72 is therefore non-conductive and oscillator (F₁) 30a does not advance counter 74.

Therefore during time interval T_1 , flip-flop 76 is in the 1 state. The state of flip-flop 78 is determined at the end of each sub-period, with its state for the subsequent sub-period determined by the state of the threshold detector at the instant that a pulse is issued by differentiator 90. If the threshold detector 50 is at a 1 state at this time, reference current is passed to the integrator 68, and oscillator pulses F₁ are accumulated by counter 74 during the subsequent sub-time interval. Conversely, if 30 the threshold detector is at an 0 state when the pulse occurs, no reference current flows to the integrator 68, and no oscillator pulses are accumulated by counter 74 during the subsequent sub-time interval.

35 The voltage E_c developed at the output of the integrator 68 is connected to threshold detector 50a, which produces an output at its terminal A that is connected to the and gate 92 and, through an inverter 102, to the and gate 100. The terminal B of the threshold detector 50a is connected to the reset input terminal of the flip-flop 82 through or gate 84. The output of the counter 34a is also connected through differentiator 86 to the "set" input of flip-flop 82 and the "reset" input of flip-flop 76.

40 In the operation of the system of FIG. 3, the start circuit 40a introduces a pulse (A in FIG. 2) which resets counters 74, 34a and 36a. In addition it resets flip-flops 78 and 82 and sets flip-flop 76. The oscillator 38a then drives the counters 34a and 36a. At the end of N_1 cycles, the counter 34a generates an output pulse through differentiator 86 (B in FIG. 2) designating the end of the time interval T_1 . During that time interval, the counter 36a produces a series of output pulses through differentiator 90 designating sub-time periods during the time interval T_1 (C in FIG. 2). The output pulse (B 45 in FIG. 2) generated by the counter 34a is also used to reset flip-flop 76 and set flip-flop 82, thereby terminating time interval T_1 and initiating time interval T_2 .

45 During the time T_1 , the current switch 64 is enabled since the counter 34a has not yet achieved its count (N_1), so that the flip-flop 76 is in the "set" state. Therefore, during the input interval T_1 , the current I_1 flows through the current switch 64 (E in FIG. 2) into the in-

egrator 68, producing a charge Q_x on the capacitor C in the integrator.

The time interval T_1 is subdivided into an integral number of sub-periods of duration T_1/A , as represented by the curve C in FIG. 2. If at the end of any such sub-period the voltage E_c exceeds E_1 , as sensed by the threshold detector 50a, then an output is produced at the output terminal A of the threshold detector which enables the and gate 92, so that the flip-flop 78 is set by the next pulse C. This enables the and gate 44a, and the reference current I_2 flows into the integrator. Since the current I_2 is of a polarity opposite to the current I_1 , the voltage E_c is reduced (curve F of FIG. 2), and an increment of charge Q_x is removed from the capacitor C in the integrator 68.

During the time interval T_2 , which follows immediately after the time interval T_1 , the current switch 64 is disabled so that the current I_1 no longer flows into the integrator 68. During the interval T_2 , however, the current switch 72 is enabled so that the reference current I_2 flows into the integrator 68. The flow of the current I_2 into the integrator 68 reduces the voltage E_c until a level of E_2 is reached, as sensed by the threshold detector 50a. When the voltage E_c reaches the level E_2 , the flip-flop 82 is reset, cutting off the flow of the reference current I_2 into the integrator 68, and terminating the interval T_2 .

Each time the reference current source is turned on, the gate 28a is enabled, so that the output counter 74 counts at a rate of F_1 . During the time interval T_2 , the output counter 74 also accumulates counts at a rate of F_1 , due to the fact that the and gate 28a is enabled.

It will be observed that the output number N_o , which equals $N_R N_{o1} + N_{o2}$, is again directly proportional to the input current I_1 , and therefore to the input voltage E_{x1} , as has been described hereinbefore for the system of FIG. 1. The output number N_o is again independent of the value of the capacitor C in the integrator 68, and of oscillator frequency, provided that these parameters remain constant during a conversion. Therefore, high accuracy is achieved easily and simply; again, since there is no dependence upon high tolerances insofar as the aforesaid parameters are concerned.

As in the system of FIG. 1, a feedback loop in the system of FIG. 3 closed around the threshold detector 50a and the integrator 68 at the termination of a reading will insure that a measurement will start and finish precisely at the E_2 level, thereby eliminating the effects of temperature drift in the threshold detector and integrator circuits.

It will be appreciated that although particular embodiments of the invention have been shown and described, modifications may be made. For example, two configurations of counting circuitry are possible.

In a first configuration, such as shown in FIG. 1, the counter 34a (N_1) accumulates count of the oscillator 38a (F_o) to generate the time interval T_1 , while another output counter 32a (N_o) is used to accumulate count of the oscillator 30a. The illustrated system permits a control of the K factor, that is the ratio between the frequency F_1 and the frequency F_o , thereby allowing digital control of scale factor, or generation of non-linear relationships between the input voltage E_{x1} and the output number N_o .

In a second configuration, K is set to unity by making F_o and F_1 the same frequency, and by using, for exam-

ple, a common oscillator to drive both the counters 32a and 34a.

In either configuration, simplification may be achieved if counter 36a (N_4) is merely the lowest order counting stages of counter 34a (N_1).

In the latter embodiment, the first counter is used during the time interval T_1 to generate the subdivisions of T_1 ; a second counter counts the subdivisions and terminates T_1 when the required number is reached; and a third counter counts the number of times during T_1 that the reference current is turned on. This third counter then contains the most significant digits of the output number. Then, during the time interval T_2 , the first counter may be used to accumulate counter pulses until the E_2 level is reached, overflowing if necessary into the third counter. The first and third counters then contain the entire output number. It is clear that the latter approach achieves a reduction in the digital circuitry requirements, since its time shares the first counter.

It is intended in the claims to cover all such modifications, and any other modifications, which fall within the true spirit and scope of the invention.

What is claimed is:

1. An integrating type of analog-digital converter system comprising:

an input circuit for producing a current (I_1) corresponding to an unknown analog input signal; an integrator circuit for producing an output voltage (E_c) in response to an input current; first gate circuit means connecting said input circuit to said integrator circuit; a reference current source for producing a reference current (I_2) of opposite polarity to said first-named current (I_1); second gate circuit means connecting said reference source to said integrator circuit; first pulse counter means connecting said reference source to said integrator circuit; second pulse counter means for producing a digital output representative of the number of pulses applied thereto; pulse generating means for generating a series of pulses;

third gate circuit means connecting said pulse generating means to said second pulse counter means and connected to said second gate circuit means to pass said pulses from said pulse generating means to said pulse counter means when said second gate circuit means passes said reference current (I_2) to said integrator circuit;

further circuitry connected to said first and second gate circuit means to enable said first gate circuit means and to disable said second gate circuit means during portions of a first, predetermined time interval (T_1) which is independent of said input current, so as to cause said first gate circuit means to pass said first-named current (I_1) to said integrator circuit during said first time interval (T_1), and to disable said first gate circuit means and enable said second gate circuit means during a second, predetermined time interval (T_2) so as to cause said second gate circuit means to pass said reference current (I_2) to said integrator circuit during said second time interval (T_2); and

threshold detector means included in said further circuit means and connected to the output of said in-

egrator circuit for causing said further circuitry to enable said second gate circuit means during sub-time periods within said first time interval (T_1) when the amplitude of said integrator output voltage (E_c) is below a selected voltage level (E_1) so as to introduce said reference current (I_2) to said integrator circuit during such sub-time periods concurrently with the introduction of said first-named current (I_1).

2. The converter system defined in claim 1, and which includes a first counter included in said further circuitry to establish said first time interval (T_1), and a second counter included in said further circuitry to establish said sub-time period within said first time interval.

3. The converter system defined in claim 1, and which includes a control network included in said further circuitry and connected to said threshold detector means for disabling said second gate circuit means during said second time interval (T_2) when the integrator output voltage (E_c) falls to a selected voltage level (E_1).

4. An integrating analog-digital converter system comprising:

an input circuit for producing an input current (I_1) corresponding to an unknown analog input signal, an integrator circuit for producing an input voltage (E_c) in response to a selected input current,

first circuit means selectively connecting said input circuit to said integrator circuit,

a reference current source for producing a reference input current (I_2) of opposite polarity to said input current (I_1),

second circuit means selectively connecting said reference current source to said integrator circuit, pulse generating means for selectively generating a series of output pulses,

first pulse counter means responsive to said output pulses to count said output pulses for a predetermined first time interval (T_1) and to enable said first circuit means for said first time interval (T_1) and to disable said first circuit means for a second time interval (T_2),

second pulse counter means responsive to said output pulses for said first time interval (T_1) to count said output pulses for said first time interval (T_1) as a predetermined number of equal sub-time periods (N_A) within said first time interval (T_1) and to generate a sub-time period output pulse at the end of each sub-time period (N_A),

third pulse counter means for producing a digital output representative of the number of output pulses from said pulse generating means applied to an input of said third pulse counter means.

third circuit means responsive to said second circuit means and connecting said pulse generating means to said input of said third pulse counter means when said reference current source is selectively connected to said integrator circuit, and

threshold detector means connected to said integrator circuit and responsive to said sub-time period output pulses and further responsive to said output voltage (E_c) to selectively enable said second gate circuit means during said equal sub-time periods (N_A) within said first time interval (T_1) when the amplitude of said output voltage (E_c) is greater than a first selected voltage level (E_1) so that said

reference current (I_2) is introduced to said integrator circuit during said sub-time periods (N_A) concurrently with the introduction of said input current (I_1) to said integrator circuit, said threshold detector means further responsive to said output voltage (E_c) during said second time interval (T_2) to enable said second circuit means when the amplitude of said output voltage (E_c) is greater than said first selected voltage level (E_1) and to disable said second circuit means when the amplitude of said output voltage (E_c) during said second time interval (T_2) is no greater than a second selected voltage level (E_2).

5. The converter system of claim 4 in which said first pulse counter means during said second time interval (T_2) accumulates said output pulses to said second voltage level (E_2), whereupon said third pulse counter means accumulates said output pulses greater than said second voltage level (E_2) so that said first and third pulse counter means accumulate the total digital output representative of the number of output pulses from said pulse generating means.

6. The converter system of claim 4 in which said pulse generating means includes a first pulse generating means selectively connected through said third circuit means to said third pulse counter means and a second pulse generating means connected to said first and second pulse counter means.

7. The converter system of claim 4 in which said first pulse counter means includes a first differentiator interposed between a first pulse counter responsive to said output pulses and first and second flip-flops responsive to said first differentiator.

8. The converter system of claim 4 in which said second pulse counter means includes a second differentiator interposed between a second pulse counter responsive to said output pulses and a third flip-flop selectively responsive to said second differentiator.

9. The converter system of claim 7 in which said first differentiator is connected to a reset input of said first flip-flop and to a set input of said second flip-flop so that an output pulse generated by said first counter means at the end of said first time interval (T_1) resets said first flip-flop and sets said second flip-flop thereby initiating said second time interval (T_2).

10. The converter system of claim 8 in which said second differentiator is selectively connected to said third flip-flop through gate means enabled and disabled by said threshold detector so that the state of said third flip-flop is determined.

11. An integrating analog-digital converter system comprising:

input means for producing a current I_1 corresponding to an unknown analog input signal,

integrator means for producing a voltage E_c which is a function of the integrated current applied to said integrator means,

I_1 control means for selectively applying I_1 to said integrator means,

start circuit means for enabling said I_1 control means to institute said application of I_1 to said integrator means,

reference current source means for producing a reference current I_2 of polarity opposite to I_1 ,

I_2 control means for selectively applying I_2 to said integrator means,

pulse generating means for generating a series of pulses,

first pulse counter means for counting said pulses, and:

- a. after a first time interval T_1 , disabling said I_1 control means for applying I_1 to said integrator means, during a second time interval T_2 and until the next enabling of said I_1 control means by said start circuit means, 5
- b. after each sub-time interval of T_1/N_1 , delivering a momentary inquiry signal, N_1 being an integer, 10
- c. registering said pulses during those intervals of time when said I_2 control means is applying I_2 to said integrator means,

threshold detector means responsive to said E_c , for 15 delivering to said I_2 control means during T_1 :

- a. an I_2 enabling signal for causing application of I_2

to said integrator means, in response to a said inquiry signal, if at that moment E_c is greater than a predetermined reference voltage E_1 , and

- b. an I_2 disabling signal in response to a said inquiry signal, if at that moment said E_c is equal to or less than said predetermined reference voltage E_1 , and for delivering, during T_2 , an I_2 disabling signal whenever E_c is equal to or less than another predetermined reference voltage E_2 ,

means for applying an I_2 enabling signal to said I_2 control means, for applying I_2 to said integrator means during time T_2 ,

means for applying said I_2 disabling signal to said I_2 control means, for stopping the application of I_2 to said integrator means, thereby to terminate T_2 .
